METHOD OF MAKING UNDERBEVELED PRINTING PLATE

Thaddeus J. Malicki, Homewood, Ill., assignor to R. R. Donnelley & Sons Company, a corporation of Delaware

Application October 30, 1957, Serial No. 693,350

4 Claims. (Cl. 101—401.1)

The present invention pertains to printing plates for cylinder presses and more particularly to underbeveled press plates and a method for their manufacture.

In certain rotary printing presses, the printing plates are secured to the plate cylinder by means of plate clips which are positioned in the cylinder and engage beveled sides of the plate to hold it in proper position. In order to obtain adequate engagement between the clip and the plate, it is imperative that a suitable clip seat be supplied to accommodate the holding device.

Where the bevel at the side of a plate extends to the top surface, the manufacture of the plate presents no problem; but where the bevel is wholly below the top surface, so as to be undercut, the machining operation requires special machine tools and the time of skilled operators to make the plates.

In accordance with the present invention, a plate with underbeveled sides is made in two parts—a backing plate and an electrotype plate; and the bevel is formed in the upper margins of the backing plate before it is joined to the electrotype plate. Thus, the two parts of the laminated plate cooperate to form the undercut grooves, or clip seats.

Since the beveling of a plate edge is a simple operation which may be performed in a number of different ways, the production of the groove slot is greatly simplified by beveling the backing plate, forming it to the curvature of the electrotype plate, and securing the backing plate to the electrotype plate to form a laminated printing plate.

It is, therefore, a primary object of this invention to provide an improved method of manufacture to produce a printing plate with an undercut clip seat.

It is a further object of this invention to provide a printing plate of laminated construction having an undercut groove in the curved end thereof.

These and other objects of the present invention will be apparent to one skilled in the art from the following detailed description when taken in conjunction with the drawings, wherein:

Fig. 1 is a perspective view of an electrotype plate;

Fig. 2 is a perspective view of a backing plate blank;

Fig. 3 is a perspective view of the backing plate which has had its edges beveled;

Fig. 4 is a perspective view of a beveled backing plate which has been formed to conform to the curvature of the electrotype plate;

Fig. 5 is a perspective view of an assembled laminated printing plate; and

Fig. 6 is an enlarged sectional view taken along the lines 6—6 in Fig. 5 which illustrates the clip seat formed by the beveled portion of the backing plate in cooperation with the electrotype plate.

Referring now to the drawings, an electrotype or other printing plate, indicated generally at 10, is arcuate as seen in Fig. 1, so as to be concentric with the surface of a plate cylinder of a rotary printing press. The printing character or intelligence is formed on the convex surface of the arcuate plate 10. A backing plate 11 is of such dimensions that it may be given the same curvature as the electrotype

plate 10 and its entire convex surface adhered to the entire under or concave surface thereof.

After the backing plate 11 is cut to the proper dimensions, the sides 12 and 13 corresponding to the curved sides of the electrotype plate 10 are beveled along their upper edges as shown at 14 and 15 in Fig. 3. The beveling may be done on any standard milling machine or in any other suitable way.

After the edges 12 and 13 of the backing plate 11 have been beveled in any suitable manner, the plate is placed in a forming die to give it the same curvature as the electrotype plate 10. An alternate method of manufacturing the backing plate 11 is to cast it in its curved form to conform with the curvature of the electrotype plate 10 and to then form the bevels thereon as described above for the flat plate. Since, however, the milling of the flat plate is somewhat easier, the first method is preferred.

After the bevels have been formed, the backing plate is positioned beneath the electrotype plate with the convex or outer curved surface of the backing plate in contact with the concave or inner curved surface of the electrotype plate, and they are adhered together by welding, brazing, or any other suitable means, such as a layer of adhesive 16, to form a laminated printing plate.

In summary, the new and improved laminated printing plate of this invention is manufactured by forming a backing plate of any suitable material to the conformation of an electrotype plate, beveling the top edges of the curved sides of the backing plate either before or after the backing plate is conformed to the curvature of the electrotype plate, and finally securing the backing plate to the electrotype plate with the beveled portion of the backing plate toward the back of the electrotype plate and the corresponding marginal portions of the electrotype plate over hanging the bevels so that the two plates cooperate to form an underbeveled groove which provides a clip seat.

The foregoing detailed description is given for clearness of understanding only, and no unnecessary limitations are to be understood therefrom, as modifications will be obvious to those skilled in the art.

1. A method of making an underbeveled printing plate for the plate cylinder of a rotary printing press comprising the steps of: providing an arcuate printing plate with a printing face on its convex surface; providing an arcuate backing plate of substantially the same size as said printing plate and of a radius of curvature corresponding to that of the printing plate; beveling two opposite edges of the convex surface of said backing plate to reduce the dimension between said edges so that it is slightly less than the corresponding dimension of the printing plate; and thereafter adhering the convex surface of the backing plate to the concave surface of the printing plate with each beveled edge of the backing plate spaced slightly inwardly from the corresponding edge of the printing plate so that the marginal portions of the printing plate overhang the bevels, whereby the beveled edges and said overhanging marginal portions cooperate to provide underbeveled plate margins.

2. A method of making an underbeveled printing plate for the plate cylinder of a rotary printing press comprising the steps of: providing an arcuate backing plate having a predetermined inside radius of curvature determined by the radius of the plate cylinder; beveling two opposite edges of the convex outside surface of said backing plate; and thereafter adhering the concave back surface of an arcuate printing plate to the outside surface of the backing plate with opposite marginal portions of the printing plate overhanging the bevels on the backing plate, whereby the beveled edges and said overhanging marginal portions cooperate to provide underbeveled plate margins.

3. A method of making an underbeveled arcuate printing plate for a plate cylinder of a rotary printing press

comprising the steps of: forming an arcuate electrotype plate having a curvature corresponding to that of said cylinder; cutting a backing plate conforming substantially to the flat dimension of said electrotype plate; removing a portion of one major surface of said backing plate to form beveled edges thereon and reduce the dimension between said edges so that it is slightly less than the corresponding dimension of the printing plate; curving said backing plate to provide it with an outer convex surface concentric with that of the printing plate, and with said reduced dimension in said convex surface; and thereafter adhering the convex surface of said plate to the concave surface of the electrotype plate with opposite marginal portions of the electrotype plate overhanging the bevels, whereby the beveled edges and said overhanging marginal portions cooperate to provide underbeveled plate margins.

4. A method of making an underbeveled printing plate for the cylinder of a rotary printing press comprising the steps of: providing an arcuate printing plate with a printing face on its convex surface; forming an arcuate backing plate having a radius of curvature corresponding to that of the printing plate and of substantially the same size

5 as the printing plate, said backing plate being formed with two opposite edges of its convex surface bevelled so that the dimension between said edges is slightly less than the corresponding dimension of the printing plate; and thereafter adhering the convex surface of the backing plate to the concave surface of the printing plate with opposite marginal portions overhanging the bevels, whereby the beveled edges and said overhanging marginal portions cooperate to provide underbeveled plate margins.
